CHAIR OR THE LIKE

Eero Saarinen, Bloomfield Hills, Mich., assignor to Knoll Associates, Inc., New York, N. Y.

Application December 22, 1948, Serial No. 150,320

Term of patent 14 years

(Cl. D15—1)

To all whom it may concern:

Be it known that I, Eero Saarinen, citizen of the United States of America and residing at Bloomfield Hills, county of Oakland, State of Michigan, have invented a new, original, and ornamental Design for a Chair or the like, of which the following is a specification, reference being had to the accompanying drawing, forming part thereof.

In the drawing:

Fig. 1 is a front perspective view of a chair, showing my new design,

Fig. 2 is a rear perspective view of the chair shown in Fig. 1,

Fig. 3 is a top plan view of the chair shown in Fig. 1, and

Fig. 4 is a side elevational view of the chair shown in Fig. 1.

The characteristic features of my design reside in those portions shown in full lines in the drawings.

I claim:

The ornamental design for a chair or the like, substantially as shown and described.

EERO SAARINEN.
